UNITED STATES PATENT OFFICE.

JAMES BARLOW, OF TRENTON, NEW JERSEY, ASSIGNOR TO JAMES MOSES,
OF SAME PLACE.

DESIGN FOR TABLE-WARE.

SPECIFICATION forming part of Design No. 19,572, dated January 14, 1890.

Application filed December 4, 1889. Serial No. 332,575. Term of patent 3½ years.

To all whom it may concern:

Be it known that I, JAMES BARLOW, a citizen of the United States, residing at Trenton, in the county of Mercer and State of New Jersey, have invented and produced a new and original Design for Articles of Table-Ware, of which the following is a specification, reference being had to the accompanying drawing, forming part thereof.

10 In the drawing, A represents the body of an article of table-ware to which my design is applied.

B represents the cover of the article, C the cover-handle, and D D the handles of the 15 body.

The article here represented is known to the trade as a "cover-dish," and the leading features of my design as applied to it are seen in the body, the cover, and the handles. The 20 body has at each corner a single scallop E, and has also near its top and entirely encircling its upper part the cove F. The cover has also,

as shown, at each corner single scallops E' E', corresponding to the scallops in the body. The handle C, as will be seen, is of ornamental shape, and has one foot divided into two parts, one part C' reaching toward the end of the cover and the other C'' bent backward toward the center. 25

Although the drawing shows my design as applied to but one article of table-ware, I can and do apply it to any and all articles of convenient general configuration. 30

What I claim as my invention, and desire to secure by Letters Patent, is— 35

In a design for an article of table-ware, the body A, with single scallops E at each corner and cove F around the upper part, as shown and described.

JAMES BARLOW.
